SHEET FEED DEVICE FOR ROTARY DUPLICATING MACHINES

Filed July 26, 1948

2 SHEETS—SHEET 2

INVENTOR.
Edgar Rütišauser
BY *Richard E.*

$$AG'T$$

invention consists in the mechanism elements and their relation one to the other, as are hereinafter more particularly described in the specification and sought to be defined in the claims.

The specification is accompanied by drawings in which:

Fig. 1 is a schematic perspective view of the device embodying features of my invention;

Fig. 1a is a detail illustrating the support of the pressing roller in the printing position;

Fig. 2 is a detail illustrating the means for the disengagement of the pressing roller from the cylinder; and

Figs. 3 to 6 are explanatory of different phases in the operation of my mechanism.

Referring now in greater detail to the drawings, a printing cylinder 1 of a single-cylinder rotary duplicating machine is supported in slots 2 in the frame of the machine in a known manner. The shaft 7 of the cylinder carries three cams 3, 4 and 5. An arm 6 is solidly connected with these cams and is provided with a slot 8 which cooperates with a clamping device 9 provided on the cylinder so that by turning of the arm the three cams may be turned and fixed jointly relative to the cylinder. The direction of the rotation of the cylinder is indicated by the arrow A.

A lever having in a starlike arrangement three arms 10, 11, and 12 swings about a shaft 13 and cooperates with the cam 3. The arm 10 carries a cam follower roller 14 riding on the cam 3. The arm 11 is connected to a linkage 15 which in turn joins a feeding or pushing roll 15a, shown in Figs. 3, 4 and 6. Connected to the linkage 15 is a member 16 (see Figs. 1 and 2) which performs an oscillating movement and bears against a plate 18. At the lower narrow side of the member 16 is an inclined surface 19 which moves along an end of a swinging rod 20.

Whenever a sheet 21 is moved by the pushing roll 15a onto the lead-in rolls 22a, 22b, a guard 24 is turned about its shaft 23 so as to allow the rod 20 to swing freely. The guard member 24, if left alone, assumes due to its own weight the vertical position and projects through an aperture 25 in a sheet metal guide 26. If the paper feed stops, the guard 24 assumes the position shown in Fig. 1, and the swinging rod 20, while one of its ends strikes against the guard 24, the other end raises the member 16.

A hook 27, by means of an adjoining cross member 16a, will also be pushed upwardly and lifted from the catch 28. Due to the pull of the spring 29 (Fig. 2), the hook will then be thrown backwardly into the dotted line position. At the end opposite to the catch 28, the hook is connected to a tilting lever 30 which carries the pressing roller 31. On unlatching the hook 27 from the catch 28, the tilting lever 30 and consequently the pressing roller 31 will be moved from the printing position into the dotted line position in which latter position the pressing roller is no longer in engagement with the cylinder 1. The tilting lever 30 is provided with an extension 32 which in the dotted line position breaks the contact 33a, 33b of the motor circuit, the dotted line position of the extension 32 conforming to the pressing roller when out of contact.

Referring to Fig. 1a, the pressing roller 31 is shown in the position in which it is in contact with the cylinder 1, that is, the printing position. The shaft 31a of the roller 31 extends beyond the roller at each of its ends, and in the printing position it is fixedly supported in ball bearings 50 and 51. The line X-X indicates the position of

the tilting lever 30 in the printing position. The tilting lever is arranged to swing about the axis 52.

In a known way, the disengagement of the pressing roller from the cylinder cannot take place unless the cylinder is in a position where no impressional pressure is exerted on the cylinder, that is, where the ends of the matrix are fixed in a flat portion 1a of the cylinder. Such an arrangement is shown, for instance, in the Swiss Patent No. 241,218. During each revolution of the printing cylinder, the flat portion 1a comes to be adjacent the pressing roller 31 once. In this position there is no contact between the cylinder and the roller 31, making it possible for the latter to be moved away from the cylinder. The position of the flat portion 1a with respect to the cams 3, 4 and 5 will be clearly seen from Figs. 3 to 5.

A cam follower roller 34 carried by a lever 35 cooperates with the cam 4. The lever 35 which is adapted to swing is provided with a curved rack 36 meshing with a gear 37 secured to the shaft 38 of the lead-in rolls 22a, 22b. A spring 39 holds the cam follower 34 above the gear 37 and the rack 36 in contact with the cam 4, thus causing the back movement of the lead-in rolls.

The lead-in rolls 22a, 22b have abutments 40 for the fed sheet 21. (There can be more such lead-in rolls provided.) The lead-in stroke for a sheet is longer than the distance from the pile of blank sheets to the abutments 40, urging each sheet to bulge, as shown in Figs. 1, 4 and 5. The lead-in rolls are knurled on their circumference to grip the sheet to be printed. When a sheet is in the curved position, auxiliary pressing rolls 42 are pressed against the lead-in rolls 22a, 22b, this being carried out from the cam 5 over the cam follower roller 43, levers 44 and 44a united by a spring 43a, and the shaft 45. There is an auxiliary pressing roll 42 to each lead-in roll. Thus, the sheet 21 comes to lie between pairs of rolls.

The feeding movement of the lead-in rolls is now started by the cam 4. The sheet of paper passes between the cylinder 1 and the pressing roller 31, and this is done in perfect registry for each preceding and succeeding sheet, thanks to the abutments 40 provided on the lead-in rolls.

As soon as the sheet 21 has run through the printing cylinder 1, the feed-in rolls 22a, 22b change their rotational direction and due to the pull of the spring 39 return to their original position in which the abutments 40 await another sheet.

The spring 47 holds the roller 14, provided on the arm 10, against the cam 3.

In Figs. 3, 4, 5 and 6, the positions of the cam follower rollers are shown. The roller 14 is the distance a, and the roller 34 the distance b, above the horizontal H-H through the cylinder axis and the cam axis, and the roller 43 is the distance c below that horizontal.

Fig. 3 also shows the pushing roll 15a in its two end positions and its control by the cam 3.

Fig. 4 illustrates the moment in which the sheet of paper fed by the pushing roll 15 toward the lead-in rolls 22a, 22b strikes against the abutments of the latter rolls. The auxiliary rolls, which are operated by the cam 5, are ready to be moved toward the lead-in rolls in the next moment to grip the paper sheet 21.

Fig. 5 illustrates the moment in which the lead-in rolls and auxiliary rolls grip the sheet of paper, and the swinging stroke of the rack 36 starts in the paper feeding direction.

Fig. 6 illustrates the moment in which the sheet of paper leaves the lead-in rolls and auxiliary rolls, and the rack 36 at the end of the feeding movement. Fig. 6 also shows the paper sheet 21 being completely fed into the machine.

Both Figs. 5 and 6 indicate that the lever 35 and rack 36 are controlled by the cam 4, and the way the lead-in rolls are oscillated about their axes by means of the rack 36.

To correct oblique printing, the shaft 38 of the lead-in rolls is carried in an arm 48 which can be swung into different positions and which is provided with a clamping device 49. If the arm 48 is moved, the shaft 38 makes an angular motion around one of its bearings. In this way the direction of the sheets to be fed is changed and, thus, the position of the area to be printed on each sheet corrected.

It will be apparent that while I have shown and described my invention in a preferred form, many changes and modifications may be made without departing from the spirit of the invention defined in the following claims.

I claim:

1. Rotary duplicating machine comprising a single rotatable printing cylinder supported in vertical guides, a pressing roller fixedly supported in a tilting lever to be in engagement with the printing cylinder during normal operation and to be out of engagement with said cylinder on interruption of the feed of blank sheets to be printed, a reciprocating pushing roll successively feeding sheets toward said cylinder, the pushing roll feeding a single sheet per revolution of the cylinder, at least two lead-in rolls and at least two auxiliary rolls in front of the cylinder, each lead-in roll and each adjacent auxiliary roll forming a pair of rolls to receive a sheet supplied by the pushing roll and to feed same forward to be received between the printing cylinder and the pressing roller, the lead-in rolls being located below, and the auxiliary rolls being located above, the sheets passing therebetween, the lead-in rolls being mounted for angular displacements in their relation one to the other, and to oscillate about their axis, the auxiliary rolls being arranged in parallel relation to the printing cylinder, and to intermittently move in and out of operative engagement with the lead-in rolls, and means to operate the printing cylinder, pressing roller, pushing roll, lead-in rolls, and auxiliary rolls, said means including cams mounted on one side of the shaft of the cylinder, and an adjustable arm solidly connected to said cams to set said cams jointly relative to the cylinder.

2. In the duplicator according to claim 1, each lead-in roll being provided with an abutment on its periphery, said abutment projecting into the sheet feed path, the lead-in rolls being stationary during the feed of a blank sheet toward the abutments, the feeding movement of the pushing roll being longer than the distance from where the paper feed starts to said abutments, which causes buckling of the leading end of the sheet, the feeding action of the lead-in rolls and auxiliary rolls starting upon striking of the leading edge of the sheet fed against the abutments.

3. In the duplicator according to claim 1, an arm provided on the frame of the machine and eccentrically carrying the shaft of the lead-in

rolls, the shaft being supported to be angularly movable with respect to the axes of the printing cylinder and pressing roller by said arm, and a clamping device provided on the arm for fastening the shaft of the lead-in rolls in the desired position.

4. The duplicator according to claim 1, comprising means to disengage the pressing roller from the printing cylinder, said means being acted upon by the means to reciprocate the pushing roll and acting on the tiltable lever, the first named means including a swinging guard, a swinging rod, and a spring-loaded hook, said guard being supported below the sheet feed path to allow sheets of paper to be fed toward the printing cylinder and to allow the swinging rod to swing freely, as long as the paper feed continues, and to arrest the swinging rod on interruption of the feed, the spring-loaded hook being connected with the tilting lever, one end of the swinging rod, on its arrest, uncoupling the spring-loaded hook, and said hook, upon its being uncoupled, tilting under the influence of its spring the tilting lever, thereby moving the pressing roller away from the printing position to an idle position.

5. The duplicator according to claim 1, comprising means to disengage the pressing roller from the printing cylinder, said means being acted upon by the means to reciprocate the pushing roll and acting on the tiltable lever, the first named means including a swinging guard, a swinging rod, a spring-loaded hook connected with the tilting lever to tilt the latter, and electric contact means positioned in the path of said hook, said guard being supported below the sheet feed path to allow sheets of paper to be fed toward the printing cylinder and to allow the swinging rod to swing freely, as long as the paper feed continues, and to arrest the swinging rod on interruption of the feed, one end of the swinging rod, on its arrest, uncoupling the spring-loaded hook, and said hook, upon its being uncoupled, tilting under the influence of its spring the tilting lever, thereby moving the pressing roller away from the printing position to an idle position, the spring-loaded hook, upon its being uncoupled, being adapted to actuate and break said electric contact.

6. The duplicator according to claim 1, wherein said adjustable arm is provided with a slot and cooperates with a clamping device on one of the front faces of the cylinder.
